PRINTING PLATE CLAMPING MECHANISM

Filed Nov. 17, 1934

INVENTOR.

Frederick ^Damott
by Albert H. Foster

ATTY.

tion 15 of the groove 12 to thrust the plate P' against or free same for movement away from the abutment block or clip 17, thus locking said plate P' to the cylinder or permitting its removal or 5 adjustment without disturbing the outer plate. Likewise, when the sleeve 23 is turned, the outer clip 16 threadedly secured thereto will thrust the plate P against or free same from the abutment 17 in both cases, it will be observed that either 10 the inner or outer plate can be removed or adjusted independently of and without disturbing the other.

The function and manner of operation has been in large measure indicated above, but may 15 be summarized as follows:

Assuming it is desired to clamp a pair of printing plates to the cylinder 11, a suitable socket wrench will be applied to the operating heads 27, 31 of the sleeve and rod 25, 24 in order to move 20 the clips 16 and 18 sufficiently away from the abutment to conveniently accommodate the plates P, P', the inner and outer bevelled edges of the said plates P and P' being engaged against the registering bevelled edges of the abutment clip 25 17. The clips are next moved in the opposite direction by the same operating means to lock the said printing plates securely on the cylinder and against the abutment.

When desired, both clips 16 and 18 may be 30 simultaneously moved by a single wrench having a double socket at one end which will engage both operating heads at once, thus permitting the simultaneous locking or unlocking of the outer and inner printing plates.

35 When required, plates of different sizes may be substituted for the plates P, P' shown in Figures 1 and 2. For example, the inner plate P' may be replaced by a plate of less width, in which case the clip 18 will first be moved to the right, in 40 order to release the old plate P'. When the old plate P' has been removed and the new width plate located, the clip 18 will be returned to its original position and into plate clamping engagement with the right hand end of the new plate. 45 The abutment 17, which previously was released by loosening the collars 32—33, is then returned to a position of operative engagement with the left hand end of the new width plate substituted for P'. The other plate P is next thrust into 50 engagement with the abutment 17 in its altered position, and the clip 16 moved into engagement with the outer end of the said plate P.

In a somewhat similar manner, the outer plate P may be replaced by another plate of greater 55 or less width, but in this latter case, the abutment 17 is not moved, the clip 16 being merely moved sufficiently further to the right or left to engage the outer end of the plate substituted for the plate P.

60 The preceding explanation, will indicate the procedure to be followed when both plates P, P' are to be replaced by plates of different widths, it being observed that, as a general rule, the clip 18 will be returned to substantially the position best shown in Figure 1, in order that the inner margin of the printed page may be uniform and of the customary width.

70 It will be noted that by means of the present design and construction, a single groove serves to accommodate a threaded rod and its coaxial sleeve, so arranged and coordinated that a plurality of clips may be actuated to engage with or be disengaged from a pair of printing plates mounted 75 on a support or independently secured, removed

or adjusted without affecting the position or adjustment of the other plate.

Those versed in the art will understand that the drawings show a portion of a conventional form of cylinder such as is used in newspaper printing machines, wherein four plates are arranged longitudinally of the cylinder and two plates around the cylinder. Thus, the inner clip 18 is substantially in the center, and the complete cylinder would carry two plates to the right of this clip as well as two to the left, as shown. When changing from plates of the dimension shown to narrower plates, it is, of course, necessary to maintain the margin space between all plates substantially unchanged, hence the provision for shifting the abutment clip 17 and also the outer clip 16. It will also be understood that in accordance with the usual practice, a plurality of clips with their adjusting mechanism are usually provided for each pair of plates, these 20 clips and their mechanism being arranged circumferentially of the cylinder.

It will be understood that the invention may be embodied in other specific forms without departing from the spirit or essential attributes 25 thereof, and it is therefore desired that the present embodiment be considered in all respects as illustrative and not restrictive, reference being had to the claims rather than to the foregoing description to indicate the scope of the invention. 30

What I claim is:

1. In a form cylinder, a plate clamping mechanism adapted to clamp a plurality of plates positioned in a longitudinal line on said cylinder, a plate clip adapted to hold adjacent edges of said plates, two additional clips, each adapted to engage edges of said plates opposite said adjacent edges, and means for operating said additional clips including screw threaded members in coaxial arrangement. 40

2. In a plate clamping mechanism, the combination of a cylinder provided with a plate support, a groove in said support, an abutment normally secured in fixed position within said groove, a pair of plate clamps slidably arranged 45 within the groove, a pair of printing plates arranged on the support in spaced relation, and other means within said groove for selectively moving either of said clamps to engage a printing plate with or disengage same from said abutment. 50

3. In a plate lockup mechanism, the combination of a plate support, a groove arranged in said plate support, an abutment plate clip for engaging side edges of two plates and normally held in fixed position within said groove but movable to various positions therein when desired, a pair of adjustable plate clips slidably mounted within said groove for engaging said plates on side edges opposite the side edges 55 engaged by the abutment clip, and a pair of manually operable members in the groove threadedly connected to said adjustable plate clips for selectively actuating either of said adjustable plate clips without disturbing any other plate clip. 60

4. In a locking mechanism of the character described, the combination of a plate support, a groove arranged in said support, a plurality of plate clips operatively arranged within said groove, one of said plate clips being normally held in a fixed position substantially central of said groove, a pair of said clips adjustably mounted within the groove, and a plurality of means arranged in the groove, one within the other, for 75

selectively actuating either of said plate clips without disturbing the other.

5. In a plate locking mechanism of the character described, the combination of a cylinder adapted to operatively support a plurality of printing plates, a groove in said cylinder extending longitudinally thereof, a pair of plate clips slidably mounted at either end of said groove, an abutment secured in the center of said groove, a tubular member within the groove for adjusting one of the slidable plate clips, and means extending through the tubular member and threadedly engaged with another of the plate clips, whereby either of the pair of plate clips may be selectively actuated to move a printing plate against or free same from the abutment without disturbing the position or adjustment of another plate engaged against the said abutment.

20. 6. In a plate lockup mechanism of the character described, the combination of a cylinder adapted to support a plurality of printing plates, a groove in said cylinder, a plurality of plate clips arranged in spaced relation in said groove, a plurality of members in the groove and threadedly engaged with the outermost and innermost of said plate clips for selectively operating the same, another clip in the groove normally serving as a fixed abutment for a pair of printing plates but adjustable to various predetermined positions when desired, means for preventing translational movement of one of said threaded members but permitting the rotation of same within the other of the threaded members, and means secured to an exterior end of each of the threaded members for selectively actuating either independently of the other.

7. In a plate lockup mechanism, the combination of a cylinder having a groove, a rod rotatably mounted in the groove, a plate abutment wherein said rod is freely rotatable, a clip threadedly mounted on an inner end of the rod, a sleeve encircling the rod, a second clip threadedly mounted on the sleeve and positioned adjacent an outer end of the cylinder, means for turning the sleeve and rod independently of each other, and means for preventing translational movement of the abutment relatively to the rod, said groove extending beyond the inner clip, whereby printing plates of various sizes may be accommodated on the cylinder and engaged and disengaged by the said clips.

8. In a plate lockup mechanism, the combi-

nation of a cylinder, a longitudinally extending groove in said cylinder, a member arranged in the groove, a plurality of widened portions formed in the groove, a corresponding plurality of plate clips arranged in said widened portions, one of said clips serving as an abutment for a pair of printing plates, a sleeve freely rotatable on said member, a clip threadedly engaged with said sleeve, means for preventing translational movement of the sleeve relatively to the member, other means for preventing translational movement of the abutment clip relatively to the member, and manually operable means protruding exteriorly of the cylinder and engaged with said rod and sleeve whereby either of said clips may be adjusted independently of the other to engage or disengage an adjacent plate independently of the other plate.

9. In a plate lockup mechanism, the combination of a plate support, a groove in said support, a threaded member arranged within the groove, a plate abutment on the member, a sleeve freely rotatable on said member but normally secured against translational movement relatively thereto, a clip threadedly engaged with the sleeve, a second clip threadedly engaged with the member, means for adjustably fastening the abutment in various predetermined positions on the member, and means on said member and sleeve for actuating same to move the said clips independently into and out of operative engagement with their adjacent plates.

10. In a plate lockup mechanism, the combination of a plate support, a groove arranged in said support, a plurality of plate clips operatively arranged in the groove, a member positioned within the groove, an abutment mounted on the member and adjustable to various positions thereon, a tubular member rotatably mounted on the first mentioned member, means for preventing movement of the tubular member axially of the first mentioned member, a plate clip threadedly engaged with the tubular member, a second plate clip threadedly engaged with the first member, and means for independently actuating the first mentioned member and tubular member whereby either of said plate clips may be selectively moved in diametrically opposite directions to lock an adjacent printing plate on the support and against the abutment clip, and to free said printing plate when desired.

FREDERICK LAMATSCH.
